Att'y

UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,393,429.

Specification of Letters Patent. Patented Oct. 11, 1921.

Application filed July 12, 1917. Serial No. 180,172.

To all whom it may concern:

Be it known that I, HENRY P. CLAUSEN, a citizen of the United States, residing at Mount Vernon, in the county of Westchester 5 and State of New York, have invented certain new and useful Improvements in Telephone Systems, of which the following is a full, clear, concise, and exact description.

This invention relates to telephone systems and particularly to trunking arrangements between exchanges. More particularly it relates to telephone systems wherein a so-called manual exchange supplies service to a private branch exchange equipped 15 with machine-switching telephone apparatus, some subscribers of which are entitled to one class of service and others of which are entitled to another class of service.

The object of the invention is to provide 20 an indicating device in a manual exchange which will notify the answering operator that a calling station from an automatic private branch exchange is or is not entitled to a specific class of service.

25 A feature of the invention is the use of the well-known line and supervisory lamps for indicating certain facts to an operator, in addition to those which they ordinarily indicate. According to this feature, the private branch exchange line, which is entitled 30 to a certain class of service, such, for instance, as unlimited or unrestricted service, when initiating a call through the use of automatic switches and a common two-way 35 trunk to a manual central office, causes the line lamp to act in the usual and well-known manner, and causes the supervisory lamp of any cord, which the answering operator may choose, to also act in the usual 40 and well-known manner. If, however, the private branch exchange line is entitled only to another class of service, such, for instance, as service restricted to local connections, toll 45 connections being denied, then means common to the trunk line and controlled by the automatic switch used in extending the connection, causes the line lamp to flash and the supervisory lamp of any cord, which the answering operator may choose, to burn 50 steadily.

Thus, the answering operator has forced on her attention the fact that the calling line may or may not be given unrestricted service. Additional apparatus is provided 55 by means of which the operator may restore

her cord circuits to normal operating conditions, so that the answering supervisory lamp may be extinguished during the actual period of conversation.

It is thought that the invention may best 60 be understood by reference to the accompanying drawing, in which a station at a private branch exchange, entitled to unrestricted service, a station at a private branch exchange, entitled to restricted service, and 65 a common two-way trunk between the central office and such a private branch exchange, are diagrammatically represented.

S¹ and S² represent substations at the private branch exchange, the first of which is 70 entitled to unrestricted service, and the second of which is entitled only to restricted service. The part to the left of the broken line including the two substations mentioned, represents the arrangement at the private 75 branch exchange, and the part to the right of the broken line represents the arrangement at a so-called manual office.

At the manual office, a cord circuit of the ordinary and well-known type, here designated C¹, is provided. A trunk line T, ending in jacks, J¹ and J² at the central office, and in a jack J³ and automatic connector switches CS¹ and CS² at the private branch exchange, is provided to supply incoming 80 and outgoing service to the private branch exchange. A line lamp LL¹, a line relay LR¹, and a cutoff relay CO¹ of ordinary and well-known construction are employed at the central office end of this trunk. A line lamp 85 LL², a line relay LR², and a cutoff relay CO² are provided at the private branch exchange end of the trunk.

Calls originating in the central office are 90 answered by an operator at the private branch exchange by means of a cord circuit C² ending in an answering plug P³ and a calling plug P⁴, by means of which the proper station is called through a jack J⁴ or J⁵. 100

Calls originating at the private branch exchange are extended through line finder switches LF¹ and LF², automatic connector switches CS¹ and CS² and thence over a common trunk T to the exchange. At this point, 105 the operator's answering cord ending in plug P¹ is equipped, in the well-known manner, with a supervisory lamp SL¹, and a supervisory relay SR¹ for controlling this lamp.

With this description of the elements of 110

the system, it is thought the invention will be fully understood by the following detail description of the operation.

A call originating in the manual exchange 5 is brought to the attention of the operator at the private branch exchange through the glowing of line lamp LL^2 , which is caused by the establishment of a circuit from ground, the upper left-hand winding of a repeating coil RC^1 , the tip of the plug P^1 , the tip of the multiple jack J^2 , thence over the lower conductor of the trunk T , through the armature and contact of the cutoff relay CO^2 , the winding of the relay LR^2 , thence 10 back over the upper limb of the trunk T , to the ring of the multiple jack J^2 , the ring of the plug P^1 , through the winding of the supervisory relay SR^1 , the lower left-hand winding of the repeating coil RC^1 , battery 15 and ground. Through this circuit line relay LR^2 is energized, which results in the establishment of a circuit from ground, inner armature and contact of relay LR^2 , line lamp LL^2 , battery, and ground. Due to the 20 resistance of relay LR^2 , the relay SR^1 is not energized in this circuit and so the supervisory lamp SL^1 at this stage of the operation is illuminated through a circuit including battery, lamp SL^1 , sleeve of plug P^1 , 25 sleeve of jack J^2 , winding of cut-off relay CO^1 to ground, and such supervisory lamp SL^1 will remain in this condition until the 30 call is answered at the private branch exchange as will hereinafter be more fully explained. At the same time, a guarding potential is placed on the third or test conductors of the connector switches CS^1 and CS^2 , through the resistance R^2 , and the alternate contact and outer armature of relay LR^2 . 35 The operator at the private branch exchange inserts the plug P^3 into the jack J^3 , whereupon the line lamp LL^2 is extinguished through the actuation of the cutoff relay CO^2 in the well-known manner, and the supervisory lamp SL^1 and the supervisory lamp SL^3 are extinguished, through the actuation of the two supervisory relays SR^1 and SR^3 , 40 which are energized; SR^1 over a path extending from ground, the upper-right-hand winding of the repeating coil RC^1 , the tip of the plug P^3 , the tip of the jack J^3 , the ring of the jack J^2 , the ring of the plug P^1 , the winding of supervisory relay SR^1 , the lower 45 left-hand winding of repeating coil RC^1 to battery and ground; and SR^3 through a circuit from ground, the upper left-hand winding of repeating coil RC^1 , the tip of the plug P^1 , the tip of the jack J^2 , the ring of the jack J^3 , the ring of the plug P^3 , the winding 50 of supervisory relay SR^3 , the lower right-hand winding of repeating coil RC^3 , to battery and ground. 55

The further extension of this call is effected in any well-known manner, through the 60 use of the calling plug P^4 and the jacks J^4

and J^5 , leading to the stations of the private branch exchange.

A call initiated by the substation S^1 may be extended by means of a line finder LF^1 , actuated in a manner well-known to one skilled in the art. By means of the manipulation of a dial switch D^1 , the subscriber S^1 may select the trunk T , and, being entitled to unrestricted service, will cause the line lamp LL^1 at the central office to burn 70 steadily, through a circuit extending from ground, impedance coil I^1 , lower talking conductor within the connector switch CS^1 , thence through the brush b^1 , the terminal t^1 , the lower limb of the trunk T , the contact 75 and outer armature of the cut-off relay CO^1 , the winding of the polarized relay PR , the winding of the line relay LR^1 , the inner armature and contact of the cut-off relay CO^1 , the upper limb of the trunk T , the 80 terminal t^2 , the brush b^2 , the impedance coil I^2 , within the circuit of the connector switch CS^1 , battery and ground. The flow of current through this circuit energizes the line relay LR^1 , but does not energize the polarized 85 relay PR^1 , due to its present direction of flow. A circuit is thereupon established from ground, the normal contact and armature of the polarized relay PR^1 , the armature and contact of the relay LR^1 , the line lamp 90 LL^1 , to battery, and ground, which causes the lamp LL^1 to burn steadily.

The operator at the central office observing the steady burning of the line lamp LL^1 , inserts the plug P^1 into the answering jack J^1 , 100 whereupon the line lamp LL^1 is extinguished through the opening of the circuit just described by the cut-off relay in the well-known manner, and a circuit established through which the supervisory relay SR^1 105 is energized and the supervisory lamp SL^1 is extinguished. The circuit extending from ground, the impedance coil I^1 , brush b^1 , terminal t^1 , the lower conductor of the trunk T , ring of plug P^1 , winding of supervisory 110 relay SR^1 , lower left-hand winding of repeating coil RC^1 , to battery, and ground, energizes the relay SR^1 , and places a shunt around the lamp SL^1 extending from battery, the contact and armature of relay SR^1 , the 115 resistance R , to the lamp SL^1 , the other terminal of which is also connected to battery and ground.

Should the substation S^2 initiate a call, the trunk will be seized, not by connector switch 120 CS^1 but by a connector switch CS^2 through the agency of line finder switch LF^2 . The trunks extended to the connector switch CS^2 are now reversed, so that the current supplied through the impedance coils I^3 and I^4 125 to the central office is reversed in direction to that supplied through the impedance coils I^1 and I^2 . In this case the polarized relay PR , as well as the line relay LR^1 will be energized and a circuit established for the 130

line lamp LL^1 from ground, the interrupter I, the alternate contact and armature of relay FR , the armature and contact of relay LR^1 , the line lamp LL^1 , to battery and ground, through which circuit the line lamp LL^1 is caused to flash, it being supplied with current when the interrupter I is on a conducting segment, and deprived of current while the interrupter I is on an insulated segment. The operator at the central office observing the flashing of the line lamp LL^1 will insert her plug P^1 into the answering jack J^1 , whereupon the energization of the cut-off relay CO^1 in the well-known manner will cause the extinguishing of the line lamp LL^1 , and bring the supervisory lamp SL^1 under the control of the calling subscriber. In this case, however, since the trunk line is reversed, battery is opposed to battery through the winding of relay SR^1 , which, therefore, remains deenergized. The supervisory lamp SL^1 continues to burn, whereby the operator has a further indication that the calling station is not entitled to unrestricted service. If such calling subscriber asks to be connected with some station through toll service, it will be the duty of the operator to deny him, but if only a local call is asked for, then the operator may extend the connection in the well-known manner.

A jack J^2 , which may be what is known as the multiple jack, has its terminals reversed so that upon such a call as that just described, from the substation S^2 the operator may place the plug P^1 in the jack J^2 , and thereby place the supervisory relay SR^1 under ordinary conditions, whereupon it will be energized and shunt out the supervisory lamp SL^1 .

40 What is claimed is:

1. In a telephone system, an exchange, a branch exchange, a two-wire trunk extending between said exchange and said branch exchange, a visual call-indicating device individual to said trunk at the exchange end thereof responsive to the initiation of a call at the branch exchange end thereof, cord circuits including supervisory relays at said

exchange, and means at the branch exchange for differently actuating said device and said 50 supervisory relays.

2. In a telephone system, an exchange, a branch exchange, a two-wire trunk extending between said exchange and said branch exchange, a visual call-indicating device individual to said trunk at the exchange end thereof, cord circuits including supervisory relays at said exchange, means at the branch exchange for differently actuating said call-indicating device and said supervisory 55 relays, and means under the control of an operator at said exchange for differently actuating said cord circuits relatively to said trunk.

3. In a telephone system, an exchange, a branch exchange, a two-wire trunk between said exchanges, multiple connections to said trunk at said branch exchange end thereof, said multiple connections being differently arranged, a visual call-indicating device individual to said trunk at the exchange end thereof, means responsive to a connection established over said trunk through one of said multiple connections for actuating said device in a particular manner, and means responsive to a connection established over said trunk through a differently connected one of said multiple connections for actuating said device in a different manner. 75

4. In a telephone system, an exchange, a branch exchange, a two-wire trunk between said exchanges, multiple connections to said trunk at said branch exchange end thereof, said multiple connections being differently arranged, a visual call-indicating device individual to said trunk at the exchange end thereof, cord circuits including supervisory relays at said exchange, means for differently actuating said device and said supervisory relays in accordance with the multiple 80 connection through which a connection may be established. 85

In witness whereof, I hereunto subscribe my name this 10th day of July, A. D. 1917.

HENRY P. CLAUSEN.
